CLAIM

The ornamental design for a gaming console, as shown and described.

DESCRIPTION

FIG. 1 is a front perspective view of a gaming console, showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

In the drawings, the solid lines illustrate the claimed ornamental design, whereas the broken lines depict portions of the gaming console that form no part of the claim.
